UNITED STATES PATENT OFFICE

2,334,311

LADY'S WEARING APPAREL

Esther Cadous, New York, N. Y.

Application December 11, 1940, Serial No. 369,550

1 Claim. (Cl. 2—227)

My invention relates particularly to women's trousers, of the type popularly known as slacks and to skirts although, it may with equal facility be applied in other types of women's wear to attain the objects hereinafter designated.

It is an object of my invention to provide a woman's garment which is readily adjustable to women of varying girths and proportions, without the need of additional cutting, sewing or other tailoring, or the use of hooks and eyes, buttons and button holes, zippers or any other form of device for moulding the garment to the body, the garment retaining at all times a graceful and tailored shape.

A further object of my invention is to provide in such a garment a combination of elastic and inelastic areas in which the line of jointure follows a curved or broken line across the width of the garment, to provide a graceful and tailored shape without the need of pleats, tucks or gathers.

It is a further object of my invention to provide waist and thigh adjustability without the need for the gathers, tucks, pleats or other surplus material in the garment, or the use of hooks and eyes, buttons and button holes, zippers or any other form of device found necessary in the prior art to assure adjustability.

Another object of my invention is to provide an adjustable garment which readily assumes a graceful appearance and readily gives a tailored, smooth and unpleated surface to the mid-section of the body.

A further object of my invention is to provide in such a garment all the advantages of a foundation girdle without the need of such a girdle as an additional item of wear.

Another object of my invention is to provide in such a garment together with the advantages hereinabove set out, a readily available novel elastic section to hold the article of attire in place without the need of an additional belt.

A further object of my invention is to provide in such a garment means for abdominal support and for the contraction of other body portions.

My invention also has for its objects such other advantages as hereinafter are made to appear.

To fully explain my invention I shall briefly refer to the disadvantages found in garments current in the art, and the principle of my invention which has made possible the improvement which is its essence.

It is a disadvantage in garments, that when purchased, it is often necessary to cut and resew them to fit the varying girth of each purchaser.

and to assure any measure of tailored appearance. It is necessary also to pleat, gather or tuck the material in the abdominal region to assure any measure of adjustability to the varying girths of purchasers. These pleated, gathered or tucked garments so styled to give a finished appearance to the garment, do not generally find favor with women wearers, the preference being for a smooth fitting flat surfaced garment about the abdominal and mid-sectional region of the body.

The use of a band of elastic fabric to form the top portion of such garments and assure adjustability does not solve the problem, since a rectangular elastic band requires the cloth of the garment along the line of jointure of both these areas, to be pleated, tucked or gathered to permit the inelastic area of the garment to expand to the increased girth. The result is an unsightly, ungainly garment lacking gracefulness in appearance. If the cloth of the garment were not pleated, tucked or gathered, the strain of the increased girth would stretch the elastic portion, but unduly strain and tear the inelastic portion.

I have discovered that all of these disadvantages may be obviated, and an adjustable garment, attaining all of the objects heretofore set out, may be made by cutting the elastic area so as to provide a line of jointure between the elastic and inelastic area of the garment following a substantially curved or broken line across the width of the garment. The principle of this type of construction eliminates the need for unsightly pleats, tucks or gathers, hooks and eyes, buttons and buttonholes, zippers, or similar devices, producing a garment which moulds to the shape of the body and fits gracefully upon the wearer. A garment thus constructed for one girth and width about the thighs and waist is readily adjustable to a woman of larger proportions. In adjusting the garment on a wearer of increased girth and width about the thighs and waist, no cutting, sewing or other tailoring is necessary. The garment is drawn onto the legs as usual and when the thighs are reached, which are usually the widest portion of the body in its lower half, no danger of abnormal strain or tearing of the inelastic fabric is present. The garment will easily pass this wider width without the need of tucks, pleats or gathers, buttons and buttonholes, zippers, or similar devices to compensate for increased width. The necessary elasticity is furnished by the elastic area which at these points curves over the surface of both thighs. The cloth along the line of jointure remains smooth and tailored.

the increase in width being efficiently furnished by the elastic areas curving over the thighs avoiding the need of tucks, pleats, gathers, and the devices above specified. If the line of jointure of elastic and inelastic fabric had been cut straight across the garment in the form of a rectangular belt section, the inelastic cloth would have been placed under abnormal strain in passing the thighs and would be so weakened as to tear, either when drawn over the thighs or in the course of wear. In instances of substantial increase in thigh width, a garment thus constructed could not be drawn over the thighs of a wearer because of the lack of elasticity in the inelastic portions of the garment. In those instances of slight increase in thigh width, the garment if successfully pulled onto the wearer leaves a tightness about the thighs, resulting in great discomfort and necessitating further cutting and tailoring. In a measure these disadvantages may be met with the use of pleats, tucks or gathers or the other devices above specified to permit some room for expansion of the inelastic area. Even when this is done the garment needs adjustment by further tailoring to produce some measure of neatness in attire.

My invention obviates all of these disadvantages. Further, it obviates the need of a foundation girdle, giving the garment the neatness, smoothness and grace of appearance sought to be attained by the use of a foundation girdle. Without more, abdominal support is provided and contraction of other body portions. The construction also permits the incorporation in the garment of an area braced by bone or spring steel strips to provide further abdominal support and contraction of body portions, leaving the garment adjustable, neat, tailored, graceful in appearance and comfortable for the wearer.

My invention is also in the combination and arrangement of parts and details of construction as herein set forth and claimed.

To clearly explain and describe my invention to others, I have shown it applied to slacks and skirts although it may be as easily applied to other articles of attire such as trousers of all kinds, pajamas, tennis shorts and other items to produce all of the objects and advantages hereinabove enumerated.

My invention is illustrated in the accompanying drawing in which:

Fig. 1 is a perspective view of one form of my invention as it will appear upon the wearer.

Fig. 2 is a front elevation of a pair of slacks shown in Fig. 1 but on an enlarged scale.

Fig. 3 is a side view in elevation of a pair of slacks showing the front and back.

Fig. 4 is a front elevation of a skirt constructed in accordance with my invention.

Fig. 5 is a front elevation of a pair of slacks showing a further modification in the line of jointure.

Fig. 6 is a front elevation of a pair of slacks showing a further modification in the line of jointure.

Fig. 7 is a front elevation of a pair of slacks showing a further modification in the line of jointure.

Fig. 8 is a front elevation of a pair of slacks showing a further modification in the line of jointure in which the elastic area is interrupted by the inelastic fabric which is carried to the top of the slacks.

Fig. 9 is a front elevation in perspective of a pair of slacks showing the provision of a section

opposite the abdomen and hinder regions, said section containing bone or spring steel members.

Fig. 10 shows an elevational sectional view taken along line 10—10 of Fig. 9 viewed in the direction of the arrow.

Fig. 11 is an elevational diagrammatic view of the section containing the bone or spring steel members.

10 Similar numbers refer to similar parts throughout the several views.

Referring more particularly to the drawing, slacks 11 are made of ordinary fabric 12, inelastic, save for the limited stretch permitted 15 by the method of cut of the warp and fill of the cloth as known to the art, which fabric comprises the main portion of the garment, the balance of said garment being made of elastic fabric 13. The elastic fabric is preferably made 20 of the type of cloth in which the threads are a combination of fabric and rubber strands, to provide elasticity in the resulting fabric. The elasticity in this fabric is in the direction of the width of the garment, in a horizontal plane, 25 being substantially inelastic along its vertical axis. This type of fabric is well known in the art.

In Fig. 1 the elastic section 13 is cut along lines to produce an area confined within the lines 14, 30 15, 16 to produce a garment fitting gracefully and smoothly over the abdomen and rear regions and particularly the hips and thighs. Line of cut 16 curved along a line which rises to a higher plane than the extreme points 17, 18 assures proper adjustability in the garment, to persons of wider girth and proportions, permitting the garment to be pulled on without tearing of the intermediate inelastic cloth area 19 and preserving the smoothness, grace and neatness of the garment. No 35 pleats, gathers, tucks, buttons, buttonholes, hooks and eyes, zippers, or similar devices are necessary.

Fabric section 12 is cut so that its upper part presents a line of cut corresponding to that of the line of cut 16 of the elastic section, so that the 40 two may be joined by stitching along the line of jointure 16 to form a single garment. To add to the appearance of the garment, a belt 20 is provided, altho this is not necessary since the garment is held in place by the elastic region 13.

50 In Fig. 3, by way of illustration, the line of jointure of the back elastic section is shown to follow a straight line. It may be made curved, identically as the front, it being permissible to vary the lines of the back and front as may be 55 desired, without departing from the invention disclosed.

In Fig. 4, the invention is shown in further modified form as applied to a skirt.

In Fig. 5 the line of jointure 16a is shown in 60 a varied form. Again in Fig. 6 it is shown as line 16b in further modified form. In Fig. 7 there is shown a further modification 16c. In Figs. 8 and 9, the lines of jointure 16d and 16e are broken in two sections. In all of these modifications the 65 principle is retained of having the line of jointure so curved that an intermediate portion of the line is in a higher plane than that of the extreme points enclosing between them an area of inelastic fabric 19.

70 In Fig. 8 the inelastic cloth area 19 is carried between the elastic sections 13—13 to the top of the garment. The result is identical.

In constructing the garment, the elastic and inelastic sections are separately cut, according to pattern and the two joined along the line of

jointure by sewing. Of course it is possible to prepare the trouser or leg region and to knit integrally with this section, a section of elastic fabric so as to produce a garment having the preferred line of jointure. In the usual method of manufacture however the garment will be made in the manner indicated out of two separate sections; the elastic, and inelastic sections then being joined as indicated.

The elastic section may be comprised of a single front and a single back portion, the two being sewed together. It may also be made of one piece, or the elastic portion may be comprised of four quarters to wit: a front and back for the left side, and a front and back for the right side, the four sections being sewed together to form one unit, this being the preferred manner of construction.

The manner of constructing this type of garment is briefly as follows, by way of illustration reference being had to the slacks disclosed in Figs. 1, 2, 3. There is first cut out of inelastic cloth pursuant to pattern a front and back portion for each of the legs of the slacks, in the drawing the right trouser being designated as 11a and the left as 11b. The tops of these portions are cut so that they will follow line 16 when appropriately joined. Then out of elastic fabric front and back portion are cut pursuant to pattern for the left and right sides, the right portions being designated at 13a, and the left as 13b. One end of these portions are cut so that they will follow line 16 when appropriately joined. The front portion of trouser 11a is then sewed onto the corresponding front portion of elastic 13a, the back portion of trouser 11a being sewed onto the corresponding back portion of elastic 13a. The left trouser is similarly constructed. The slacks are then completed by sewing along seams a, a and b, b, to the top of the garment, along the crotch region and along line 24 in front and back. The resulting garment has the desired line of jointure between elastic and inelastic fabric. From this description the manner of construction of a skirt is obvious, as well as other types of garments which may be made in accordance with my invention.

In Fig. 9 there is disclosed a modification of my invention in which the garment is provided with sections 21 front and back. In constructing said sections inelastic fabric is cut to a size and shape corresponding to lines c, d, e, f, and g as shown in Fig. 11. Onto one face of the section there are affixed stays 22 either of bone or spring steel. These are confined upon the surface of the sec-

tion by sewing strips of tape 23 over them. The sections, thus completed are then made part of the garment by sewing the same within the garment, front and back as indicated by sewing along lines c, d, e, f, and g as shown in Fig. 9.

In inserting sections 21 within the garment, in the modifications of my invention shown in Figs. 9, 10 and 11, outer seams a and b are left unsewed for a short distance commencing below points 17 and 18 and along lines 14, 14. In this condition of the garment sections 21, front and back are readily fitted within the garment, against the corresponding elastic sections, and are then stitched along lines c, d, e, f, g, to permanently affix the same to the garment. The bottom line of said sections shown in dotted lines in Fig. 9 is left hanging free and unsewed. The garment is then completed by completing the sewing of seams a and b to the top of the garment. The result is a garment which has the additional features of added support and contraction for these portions of the body, to assure in certain instances, additional neatness and grace in the wearing of ladies apparel.

If desired the garment may be provided with an elastic section in the front alone, or with the elastic section in the back alone, leaving the front or back respectively of inelastic fabric, if it is desired to obtain the advantages of my invention on one side of the garment. I prefer to use an elastic section, however, in back and front.

Various changes in the form, proportion and the details of construction may be resorted to without departing from the principle or sacrificing any of the advantages of this invention. Altho I have explained my invention with a certain degree of particularity, it is understood that my present disclosure has been made only by way of example.

Having thus described my invention, I claim:

A garment having a lower part of inelastic fabric to conceal the lower limbs of the wearer; an upper elastic band about the waist and thigh regions of elasticity across the width of said garment, said elastic band being shaped widest at the thigh regions and of graduating narrower width across the midsection of the body of the wearer; and a smooth flat seam uniting said band at its lowermost boundary with the lower part of said garment, whereby the region of union remains sufficiently elastic across the width of the garment to varying girths, to conform the same to the shape of the wearer.
